UNITED STATES PATENT OFFICE.

JOHN R. BITNER, OF CLEVELAND, OHIO, ASSIGNOR OF ONE-THIRD TO
SAMUEL HEIMLICH.

RAIL-JOINT BED-PLATE.

SPECIFICATION forming part of Letters Patent No. 728,190, dated May 19, 1903.

Application filed January 19, 1903. Serial No. 139,573. (No model.)

To all whom it may concern:

Be it known that I, JOHN R. BITNER, a citizen of the United States of America, residing at Cleveland, in the county of Cuyahoga and State of Ohio, have invented certain new and useful Improvements in Rail-Joint Bed-Plates; and I hereby declare the following to be a full, clear, and exact description of the invention, such as will enable others skilled in the art to which it pertains to make and use the same.

This invention relates to an improvement in a rail-joint bed-plate.

The object of this invention is to provide a device of this description which will be both strong and durable and which can be very cheaply manufactured.

Another object of this invention is to provide a device of this character which can be readily placed in position and adjusted upon rails which are already laid without any change or alteration of the angle-plates now in general use.

My invention therefore consists in the features of construction and combination of parts hereinafter described in the specification, pointed out in the claims, and illustrated in the drawings.

Referring to the accompanying drawings, Figure 1 is a plan view of my device before it has been adjusted on the rails. Fig. 2 is a section on line 2 2, Fig. 1. Fig. 3 is a plan view showing my device adjusted on the adjacent ends of two rail-sections which are secured together by angle-plates of the ordinary construction. Fig. 4 is a section on line 4 4, Fig. 3.

Again referring to the drawings, *a* represents a metallic plate, preferably of pressed steel. At each side of the plate *a* are formed wings *b*, *c*, *d*, *e*, *f*, and *g*. The wing *c* is preferably shorter than the other wings. Along each side of the plate *a*, adjacent to the wings, is formed a rib or ledge *o* and *p*, respectively. These ribs or ledges *o* and *p* extend longitudinally the full length of the plate *a*, and each of the said ledges is arranged so that it will come under the outer bottom edge or toe of the adjacent angle-plate when the device is adjusted on the rail and form a base therefor. At each side of the respective ledges *o*

and *p* are formed grooves *h* and *l* and *m* and *n*, respectively. The grooves *l* and *m* are arranged so that they approximately correspond with or come just below the outer edge of the base of the rails. The grooves *h* and *n* are arranged so that they come just below the outer edge of the respective angle-plates. These grooves greatly facilitate the adjustment of the device on the rails, as slight variations in the rails can thereby be accommodated.

In the plate *a*, adjacent to the wings *e* and *g*, are formed slots *r* and *s*, which extend transversely of the said plate. These slots are so arranged that when the plate is first placed in position under the rails a portion of each slot will extend under the rails and the portion of the slot exposed will be somewhat less than the cross-section of the spike at its thickest part, so that the driving of the spike will have a tendency to draw the plate toward the side at which the spike is driven. In the center of the plate *a* and extending longitudinally thereof are formed strengthening-ribs *a'* and *a''*. These strengthening-ribs *a'* and *a''* are preferably formed by pressing the plate so as to form a longitudinal slot *a³*, and the depressed material of the plate forms the said ribs.

Before the plate *a* is placed in position the wings *b* and *d* are curved, so that they will conform to the curvature of the angle-plate on the side of the rail adjacent to them, and the wing *c* is bent up so as to form a stop. The spikes are then inserted in the respective slots *o* and *p* and when driven into the ties draw the plate *a* over and cause the wings *b* and *d* to bind closely on the angle-plate. The wing *f* is then bent up on the opposite side of the angle-plate by any suitable device. It will readily be seen that the manner of bending or the side at which the wings are first bent would depend upon the circumstances in each case, and therefore form no part of my invention.

What I claim is—

1. The combination, with two rail-sections and the angle-plates securing the adjacent ends of said sections, of a metallic plate arranged below the said ends, curved wings formed on the sides of said plate and arranged

- to lap over the lower ends of said angle-plates, flat wings arranged to alternate with the said curved wings, transverse slots formed in said plate adjacent to the flat wings and arranged 5 so that a portion of each slot will be covered by the said rail-sections and spikes arranged in said slots so as to bear against the outer ends of the rail-sections and the outer end walls of the said slots, substantially as described 10 and for the purpose set forth.
2. A rail-joint bed-plate comprising a metallic plate provided with a series of curved wings arranged on each side thereof, a series of flat wings arranged to alternate with the 15 said curved wings, slots formed in said plate adjacent to the said flat wings and a ledge formed on the upper surface of said plate at each side thereof, substantially as described and for the purpose set forth.
3. A rail-joint bed-plate comprising a metallic plate, a series of curved wings formed on each side of said plate, a series of flat wings arranged to alternate with the curved wings, slots formed in said plate, two parallel 25 ledges formed on the upper surface of said plate and extending longitudinally thereof and strengthening-ribs arranged on the bottom of said plate, substantially as described 30 and for the purpose set forth.
4. A rail-joint bed-plate comprising a metallic plate, a series of curved wings formed on each side thereof, a series of flat wings, arranged to alternate with the curved wings, two parallel ledges formed on the surface of said plate and extending longitudinally thereof and grooves formed at the respective sides 35 of said ledges, substantially as described and for the purpose set forth.
5. A rail-joint bed-plate comprising a metallic plate provided with two curved wings projecting at one side, a third curved wing projecting from the opposite side and arranged centrally between the first-mentioned wings and slots formed in said plate, substantially 45 as described and for the purpose set forth.
6. A rail-joint bed-plate comprising a metallic plate, two curved wings formed at one side of said plate and arranged to grip upon the angle-plate adjacent thereto, a curved 50 wing formed on the opposite side of said plate
- between the first-mentioned wings and arranged to grip upon the angle-plate adjacent thereto, flat wings formed on said plate on each side of said last-mentioned wing and transverse slots formed in said plate adjacent 55 to the flat wings, substantially as described and for the purpose set forth.
7. The combination, with two rail-sections and the angle-plates securing the adjacent ends of said sections, of a metallic plate, 60 curved wings formed on opposite sides of said plate and adapted to embrace the lower ends of said angle-plates, two ledges formed on said plate and arranged to extend longitudinally under the respective angle-plates and 65 transverse slots formed in said plate substantially as described and for the purpose set forth.
8. The combination, with two rail-sections and the angle-plates securing the ends of said 70 sections, of a metallic plate arranged below said ends, curved wings formed on the sides of said plate and arranged to lap over the lower end of said angle-plates and grooves formed in the surface of said plate adjacent 75 to the said wings and extending longitudinally of the said plate, substantially as described and for the purpose set forth.
9. The combination, with two rail-sections and the angle-plates securing the ends of said 80 rail-sections, of a plate arranged below the ends of said rail-sections, a curved wing formed integral with the said plate at one side thereof and arranged to lap over the lower end of the adjacent angle-plate at the joint 85 of said rail-sections, two curved wings formed integral with said plate on the opposite side thereof and arranged to lap over the lower end of the adjacent angle-plate at each side of the joint of said rail-sections and means 90 for securing said plate in position.
- In testimony whereof I sign the foregoing specification, in the presence of two witnesses, this 11th day of January, 1903, at Cleveland, Ohio.

JOHN R. BITNER.
